(57) **CLAIM**

The ornamental design for a hand controller apparatus for a medical device, as shown and described.

DESCRIPTION

FIG. 1 is a perspective view of a hand controller apparatus for a medical device.

FIG. 2 is a front view of the hand controller apparatus of FIG. 1.

FIG. 3 is a rear view of the hand controller apparatus of FIG. 1.

FIG. 4 is a left side view of the hand controller apparatus of FIG. 1.

FIG. 5 is a right side view of the hand controller apparatus of FIG. 1.

FIG. 6 is a top plan view of the hand controller apparatus of FIG. 1; and,

FIG. 7 is a bottom plan view of the hand controller apparatus of FIG. 1.

The broken lines illustrate portions of the hand controller apparatus for medical device that form no part of the claimed design.
